[57] CLAIM

The ornamental design for a molding, as shown and described.

DESCRIPTION

FIG. 1 is a front perspective view of a molding showing my new design;

FIG. 2 is a top plan view thereof, the center being broken away to show indeterminate length;

FIG. 3 is a right end elevational view, the left end being a mirror image thereof; and,

FIG. 4 is a front elevational view thereof.

FIG. 1

FIG. 2

FIG. 3

FIG. 4
